DRUM CRADLE

William A. Williams, Philadelphia, Pa., assignor
to The American Pulley Company, Philadelphia, Pa., a corporation of Pennsylvania

Application June 2, 1947, Serial No. 751,672

1 Claim. (Cl. 248—143)

1
This invention relates to cradles for drums or the like and, though capable of a variety of applications, is particularly useful as applied to large drums, barrels or like cylindrical objects; the primary purpose of the invention being to simplify the operations of elevating and positioning a drum for drainage.

Heretofore various forms of trucks, cradles or other drum handling devices have been proposed to enable a single operator to effect the desired movement of a drum from one position to another, and I am aware that these have included wheeled frames with devices for securing a drum thereto so that it can be elevated and transported or turned through an angle to drain the contents into smaller containers. Such devices, as far as known to me, have involved complicated mechanical parts and have been difficult or expensive to manufacture and cumbersome to operate.

The cradle of the present invention is extremely simple in its construction, involves no mechanical linkages or parts which may get out of order, and yet possesses all of the advantages, especially as to versatility and ease of operation, which have characterized such drum handling devices of the prior art. In addition the cradle of my invention has a novel handle and housing for the same in which the handle is rotatably and slidably mounted so that in one position it may serve as a lever for gripping the drum and turning the cradle with the drum thereon through an angle, as from a perpendicular to a horizontal position, or vice versa; and in another position it may be housed within the cradle frame clear of the drum head so as not to interfere with draining the drum and so as to reduce the total bulk of the cradle when not in use. Desirably also this handle is so designed and applied to the cradle frame that it is not normally separated therefrom and hence is unlikely to be mislaid, but is nevertheless capable of being removed from the cradle, the handle being so designed that it has separate utility as an upending lever for drums. Additionally the handle may be used as a means for guiding or steering the cradle, either with or without a drum upon it.

Other objects and advantages characterizing my invention, including simplicity of manufacture and assembly of the constituent elements, will be more apparent from the description hereinafter set forth of one embodiment or example of the invention, having reference to the accompanying drawings whereof:

Fig. 1 represents a side elevation of a drum cradle of my invention showing the cradle as ap-

plied to a conventional drum in a vertical position;

Fig. 2 represents a side elevation of the same with portions of the cradle and drum broken away, and showing the drum in a horizontal position in readiness for draining;

Fig. 3 represents a cross section of the same taken as indicated by the arrows III—III of Fig. 2;

Fig. 4 represents a side elevation of the cradle 10 in an inclined position, with parts thereof shown in section and with its handle shown in an extended position where it may be used for guiding and steering the cradle;

Fig. 5 represents a drum, with portions thereof shown in section, and with the handle removed from the cradle and applied to the drum as an upending lever;

Fig. 6 represents an exploded perspective view showing the various parts of the handle prior to their assembly into an integral unit; and

Fig. 7 represents a perspective view of the housing for the handle showing how it is joined to the cradle frame.

In the drawings a cylindrical drum of a conventional type is represented at 1. By removal of a fitting 2, which normally closes an opening in the upper head of the drum, a spigot 3, shown in dot-and-dash lines in Figs. 2 and 3, may be applied to the drum in a customary manner so that the contents may be drained when the drum is turned from a vertical to a horizontal position.

The cradle frame 4 includes side members 5, which are curved throughout a portion of their length to provide rockers to facilitate turning of the drum, and longitudinal members 6 which are joined by transverse bars 7, curved to conform to the cylindrical contour of the drum. At the ends of the rocker members 5 a pair of flat prongs 8 are provided for engaging the drum beneath the lower head in the manner shown in Fig. 1. The prongs 8 may be readily slid beneath the edge of the drum and serve to sustain its weight while it is being turned in one continuous operation from a horizontal position to a vertical position, or vice versa.

At the opposite end of the rocker frame 4 a longitudinally slotted tubular housing 9 is joined to the back of the transverse bar 7 at its medial portion, as shown most clearly in Fig. 7. The housing 9 serves to accommodate a handle 11 which is slidably and rotatably mounted therein. It will be observed that the slot 12 extends continuously from one end of the housing 9 to the other, permitting the passage therethrough of

a thin flat hook-shaped piece 13 which is integrally joined to the handle between the ends thereof.

Desirably the cradle frame is equipped with spaced pairs of wheels 14, 15. In the illustrated example of the invention the wheels 14 are mounted on an axle 16, whereas the wheels 15 are journaled within the cradle frame beneath a transverse member 17.

As shown in Fig. 6, the handle 11 consists of a tubular bar having a flat piece 18 attached to its inner end serving as an abutment which is adapted to engage the inner end of the tubular housing 9 and thus to limit outward movement of the handle. The hook 13 is so designed that when a drum is in contact with the front faces of the transverse bars 7 it can be brought into engagement with the chime at the upper drum head, in the manner illustrated in Figs. 1 and 2, causing the drum to be firmly gripped and held against the cradle frame. The handle 11 is rigidly aligned within the tubular housing so that it may act as a lever for effecting any desired movement of the cradle. It is also capable of being removed from the cradle frame in which event it may be applied separately to a drum in the manner shown in Fig. 5, and used as an upending lever, or for inclining a drum, or for accomplishing various other movements, especially where the weight of the drum and its contents does not require the use of the cradle.

The operation of the drum cradle is extremely simple. In turning a drum from a vertical to a horizontal position in order to drain the contents the cradle is first advanced to a position, as shown in Fig. 1, in which the spaced prongs 8 abut against the lower drum head at opposite sides thereof and the hook 13 of the handle is brought into engagement with the chime at the upper drum head in the vicinity of the fitting 2. After applying the spigot 3 the operator grasps the handle 11 pulling it towards himself while bearing down with one foot against the wheel axle 16. As the drum is tilted and when it reaches an angle of about fifteen degrees from its original vertical position and before the drum is completely lifted from the ground, the prongs engage under the chime at the lower drum head so that they support the weight of the drum. With further tilting of the cradle the drum moves into snug engagement with the transverse bars 7 and the drum is thereafter fully supported by the cradle as the turning movement proceeds about the rocker members 5. Thus all of the steps of coupling the drum to the cradle and turning these elements through an angle are performed as a single continuous operation which can be effected with ease by a single operator. Moreover, the cradle frame 4 is so designed and the drum so balanced thereon that the above described movements do not require great strength and may be performed quickly and smoothly. When the drum is in the horizontal position it can be transported from one location to another by wheeling the frame using the handle 11 in its extended position for guiding and steering it.

With the drum in position for drainage the handle 11 is first withdrawn from engagement with the drum, then turned within its housing 9 until the hook 13 registers with the slot 12, and then retracted inwardly towards the cradle until it assumes the housed position shown in broken lines in Fig. 2. In its retracted position the handle is clear of the drum head so that it does not interfere with the operation of draining the con-

tents into a receptacle placed beneath the spigot 3. In an obvious manner by a reversal of the above described operations the drum may be returned to a vertical position.

It will be noted that by setting the handle 11 in the position shown in Fig. 4, in which the hook 13 abuts against the outer end of the housing 9, the cradle by itself may be wheeled from place to place. A pulling force applied to the handle 11 will not dislodge it but will merely cause the stop 18 to abut against the inner face of the housing 9. Similarly when a drum is carried on the cradle the handle 11 may be used to push or pull the cradle as well as to steer the same, all of which can be accomplished by one hand of the operator.

Although, as mentioned above, it is possible to remove the handle 11 from the cradle frame 4 by sliding it inwardly through the tubular housing 9 and withdrawing it from the opposite end of the frame, under ordinary circumstances the handle is retained within the cradle frame in association with the housing 9, it being unnecessary to dislodge it to accomplish any of the operations of rocking or transporting a drum, and therefore the handle is unlikely to become mislaid through any inadvertence on the part of the operator.

It will be seen that a cradle frame constructed as described and illustrated herein can be very cheaply manufactured and yet may be used to accomplish a variety of purposes. Such a frame avoids the use of any parts which are difficult to assemble or are apt to get out of order. It may be readily adapted to fit a drum of any size or to handle other similar objects. Moreover, such a cradle frame may be used to advantage with or without the provision of wheels.

Although I have described a specific example of the invention by reference to one embodiment which I prefer to use, it will be obvious to persons skilled in the art that various modifications may be made in the form of the cradle or the handle, including modifications with respect to the type of housing with which the handle cooperates, all without departing from the spirit of the invention as defined in the annexed claim.

Having thus described my invention, I claim:

A drum cradle comprising a skeleton rocker frame including longitudinal drum supporting members joined by a transverse bar, said bar being curved to conform generally to the cross-sectional shape of a drum, an axially slotted handle housing disposed longitudinally within said skeleton rocker frame, an operating handle mounted in said slotted handle housing with capacity for rotary and axial movement, and a chime-engaging element integrally mounted on said operating handle to cooperate with said slot in said handle housing to allow said handle to be housed in said skeleton rocker frame.

WILLIAM A. WILLIAMS.
